FURNACE STRUCTURE

Otto J. Kuenhold, Shaker Heights, Ohio, assignor to The Forest City Foundries Company, Cleveland, Ohio, a corporation of Ohio

Application October 17, 1931, Serial No. 569,433

17 Claims. (Cl. 126—116)

My invention relates to a furnace structure and, particularly, to an auxiliary warm air heating furnace designed especially for fluid fuel and adapted to be used in conjunction with the usual domestic coal furnace so as to utilize the same air circulating ducts, registers, etc.

The objects of my invention are to provide an auxiliary air heating furnace so constructed as to obtain the highest attainable efficiency combined with compactness to fit restricted quarters; to provide a furnace designed for ease and speed of erection; to provide a single standard construction which may be assembled to suit location relative to the coal furnace, for instance, right or left-hand side, and which will adapt itself to practically any domestic warm air heating plant with least possible special planning or changes to the existing system; to provide a furnace that will adapt itself with certainty of successful operation and no interference with the operation of the existing system so that the auxiliary furnace and the existing furnace can be used separately or together; and to provide an auxiliary furnace embodying the greatest simplicity as to erection and operation.

Various other objects and advantageous features of my invention will be seen in the following description and one embodiment thereof may be seen in the accompanying drawings wherein similar characters of reference designate corresponding parts, and wherein:

Fig. 1 is a perspective view showing an auxiliary furnace constructed in accordance with my invention and connected to a furnace of the coal burning type; Fig. 2 is a perspective view showing the opposite sides of the auxiliary furnace from those shown in Fig. 1; Fig. 3 is a perspective view of a motor fan unit for creating a forced draft through the auxiliary furnace; Fig. 4 is a transverse vertical section of the auxiliary furnace shown in Figs. 1 and 2; Fig. 5 is a longitudinal vertical section through the center of the auxiliary furnace; Fig. 6 is a longitudinal vertical section through the bottom portion of one of the side drums employed in the auxiliary furnace; Fig. 7 is a horizontal section through the auxiliary furnace and showing the burner structure in plan; Fig. 8 is a front elevation of a part of the auxiliary furnace showing the fire door in closed position; Fig. 9 is a view similar to Fig. 8 showing the fire door in open position; Fig. 10 is a transverse vertical section of the lower end of one of the side drums; Fig. 11 is a fragmentary perspective view showing the casing panel assembly; Fig. 12 is a view showing the front

support for the side drums; Figs. 13 is a plan view, partly in section, showing the connections between the side drums and the combustion products exhaust, and the rear support for the side drums and middle drum; Fig. 14 is an enlarged sectional view of the burner structure; and Fig. 15 is an enlarged view of the hot air control gate, showing the gate in closed position.

Referring to the drawings, I have shown one embodiment of my furnace structure designed to be used in conjunction with a coal furnace of the usual type and indicated by A in Fig. 1, as comprising a casing divided into front and back panels 1 and 2 and two side panels 3 and 4, these panels being joined at their meeting edges by interlocking joints as shown in Figs. 4, 7, and 11. To secure the front and back casing panels 1 and 2 in place, the panels are bent reversely and then inwardly to form a portion 5 that is L-shaped in cross section, see Figs. 7 and 11. This serves, as one of its purposes, to stiffen the front and back panels against bending during erection or handling. The side panels 3 and 4 are provided on each of their edges with inwardly extending flanges 6 which interfit with the reversely bent L-shaped portion 5 of the front and back panels. A brace 7 is spot welded to the front and back vertical edges of the front, back and side panels, and when they are nested as shown in Fig. 7, a single bolt or rivet 8 inserted in matched holes at each joint secures the joints to form a substantial structure, the front and back panels being spaced apart by the inwardly extending flanges of the L-shaped portions 5 on the front and back panels 1 and 2.

Suitable means are provided for securing the bottom portion of the corner joints. This means consists of a bottom stiffener angle 9 welded to the front and back casing panels 1 and 2, these stiffener angles being shaped to the bottom of the entire structure and of a size therewith. One of the legs on two opposing sides of the stiffener angle is preferably bent upwardly at about a 60° angle prior to assembly, see Fig. 11, whereupon, after the side casing panels 3 and 4 are properly nested with the front and back panels 1 and 2, and aligned and bolted by the bolts 8, these legs 9 may be bent upwardly to secure the bottom portion of the side panels 3 and 4 in proper position relative the front and back panels 1 and 2. Thus, the entire vertical portion of the casing structure may be assembled with the employing of only four bolts that are readily accessible, yet a very rigid structure is provided. With

this construction, it will be apparent that the side panels 3 and 4 are interchangeable.

One of the interchangeable side casing panels 3 and 4, in this instance, the panel 3, is provided with an air inlet opening 10 and an air outlet opening 11, the openings being provided with outwardly extending flanges 12 and 13 at all edges. A casing top 14 slants upwardly toward the outlet opening 11. The top 14 is provided with upwardly extending flanges ending in hooked shape portions 15 which hook over the top edge of the furnace casing panels as shown in Fig. 4. Thus, a receptacle is formed at the top of the casing which may be filled with sand or other heat retardant and an upper cover 16 is provided for lending the casing structure a neat appearance and, at the same time, add an air space for additional heat insulation. With this construction, the slanting top 12 may be reversed so as to slant upwardly toward the outlet whether this be on either right or left side as may be required.

Each casing panel is provided with an inner lining sheet 17 spaced from the panels to provide an air space for heat insulation, the air space being open at both top and bottom so as to provide for free circulation between the linings and the outer casing panels. This lining extends upwardly substantially to the level of the lowest portion of the slanting top 12 and is of the same height at the front, back, and sides of the casing with the exception of a cut out portion in one side to receive a hot air gate and control that will be hereinafter described. The interchangeability of the side panels 3 and 4 and reversibility of the top 14 provides an auxiliary furnace structure that is well adapted for use on either side of the heating unit of an existing heating system.

Disposed within the casing just described, is a circulating air heating means consisting of a central drum 18 having a burner element 19 therein and two side drums 20 disposed alongside the central drum 18. In this instance, there is one drum 20 on each side of the central drum 18. However, it will be understood that there may be one or more side drums on each side of the central drum, the number being governed by the conditions which the furnace structure is constructed to meet. The side drums 20 are operatively connected with a central drum by means of tubular connecting ducts 21 which may be of any number desired and the lowermost ends of the side drums 20 connect with a hollow U-shaped vent manifold casting 22 that has its central portion projecting rearwardly through the back casing panel 2 as shown in Figs. 2 and 13 by means of sleeve connections 22'. The passages in the vent casting 22 pass diagonally through the casing to the vertical vent duct 23 as shown in Fig. 13. This gives a method of transferring the vent gases from the side drums to the vertical vent pipe having greatest directness and least flow resistance which is important in securing efficient results. This U-shaped manifold casting 22 has an outlet at its top, communicating with the vertical vent passage 23 which vents into an open draft hood 24 which, in turn, vents through an outlet opening 25 into the chimney by way of a suitable connecting pipe. The entire drum assembly is supported by the front and back casing panels 1 and 2, and the side drums 20 are secured to the middle drum by means of the communicating ducts 21, cross plates 26 at the front of the casing which bolt to the front casting 28, and rear cross supporting

members 27, see Figs. 4, 7, 12 and 13. Such rear cross supporting member 27 is bolted to the vent manifold casting 22 with which the side drums are assembled and through the middle drum and the rear lining plate 29 of such middle drum. The rear vent manifold casting 22 rests on the rear casing panel through which it projects. As to the front casting 28, this is securely bolted to the middle drum before assembly of the furnace, and when the furnace is assembled it is bolted to the front casing panel so as to support the weight of the front end of the entire drum assembly. The above described drum assembly including drums 18 and 20 and the rear vent manifold casting 22 may be secured to the end 15 shipped as a unit apart from the casing panel.

The side drums 20, which have sheet metal sides and ends, have the lowermost edges of the sides as well as the front end bent inwardly as shown at 30 in Fig. 10. A bottom casting 31 is provided to receive the sheet metal sides and ends and a series of toggle clamps 32 (see also Fig. 7) hold the sheet metal in engagement with the casting 31. That is, when the nuts on bolts 33 are tightened the toggle clamps not only pull the sheet metal into firm engagement with the casting 31 but also push the sheet metal outwardly and tightly against vertical flanges 34 on the casting 31. As shown the bolt holes in the casting 31 have a vertical extension 35 that is sufficiently high to be above any possible water line and thereby prevent leakage of water of condensation from the drums at this point. The tops of the middle drum 18 and the side drums 20 have a similar construction except that the top 35 castings 36 are level across the entire length of the drum. However, the bottom castings 31 are pitched downwardly toward the rearward ends of the drums for drainage purposes, see Fig. 6, the bottom of the U-shaped vent casting 22 being lower than the bottom castings 31 of the side drums so that moisture will drain into the vent casting and then out of a drainage opening 36' provided therein for such purpose, see Fig. 13. This opening provides a drain for the entire combustion system.

As hereinbefore stated, the middle drum 18 is provided with a burner 19 that is preferably a one-piece cored casting having flame jets 37 on the top thereof, the casting being symmetrical about its vertical transverse and longitudinal central planes and having supporting lugs 38 at its ends, see Fig. 5. At the rearward end of the burner, the lug 38 fits into a socket 39 in the rear lining casting 29 while, at the front, the lug 38 fits in a socket 40 that takes the form of an inverted U. Thus, to secure the burner in place, the burner is first seated in the rear socket 39 and then the front end of the burner is moved upwardly so that the front burner lug 38 will fit in the inverted U socket 40. A screw 41 projects through the front casting 28 and below the front burner lug 38, see Fig. 5, to hold the burner securely in place. The lugs 38 are preferably of rectangular cross section so as to prevent rotative movement of the burner after the lugs are disposed in the sockets, and a mixer 42 is secured to the burner with its outer end fitting within a recess 43, see Fig. 9, in the front casting 28. The above described method of securing the burner in place permits the fuel control valve to be screwed into the end of the mixer and fuel pipe connection to be made directly thereto without other means of support.

To protect the side sheets of the middle drum 75

18 from excessive heat radiation at points adjacent the burner element therein, lining plates 44, preferably of cast iron, are disposed adjacent the burner, see Figs. 4 and 7. To retain the linings in place during shipment and use, a sheet metal strip 45 is welded or riveted to the sides of the middle drum whereby the top end of this strip may be bent over the side linings as shown in Fig. 4. This method is employed because it 10 affords easy replacement of the side linings in case of their cracking or warping or in case of internal explosion. With this construction, the side linings can bulge outwardly without tearing loose from its fastening means or cracking the 15 side lining plates. Likewise, a front end lining 46 is provided to correspond to the rear end lining 29 hereinbefore mentioned.

To achieve the desired distribution of air to all flame jets of the burner element 19, the air 20 openings around the burner are relatively narrow. That is, the side combustion chamber linings 44 have inward extensions 48 that extend toward the burner, leaving only very narrow slots 49 on each side of the burner and the front and 25 rear linings 46 and 47 are provided with shelf extensions which extend towards the ends of the burner to provide a similar slot 50 at each end. The central space between the two cored passages of the burner is provided with a baffle 30 51 which closes the opening between the passages except for very narrow slots 52 on each side of the baffle. By separating the two cored longitudinal passages of the burner and having the baffle 51 in between with a narrow air slot 35 53 on each side, the air is guided toward the flames in such manner as to prevent the flames of the two longitudinal parts of the burner from drawing together and merging.

Provision of these restricted air inlets and the 40 distribution of air resulting therefrom results in the aeration of the flames being more uniform from front to back of the burner in spite of the fact that the air, in the preferred construction, enters the space 53 below the burner only at one 45 end. That is, the air entering the combustion space 54 around and above the burner is diverted slightly toward the flames where needed; but not so much as to cause blowing of the flames and the flames are shorter and snappier 50 than they would be otherwise. Needless surplus air is eliminated giving combustion products of higher temperature and making possible greater heat transfer from the amount of heating surface employed, and results in the exhaustion of 55 the vent combustion products at a temperature safely above the condensation point yet with an unusual high furnace efficiency for that combustion products temperature.

In order to have the auxiliary furnace fit any 60 domestic warm air heating plant, for example, a coal furnace, regardless of whether the coal furnace has a cold air intake duct leading from the outside or takes its cold air directly from the basement, the auxiliary furnace is arranged to 65 receive its cold air supply from the base of the coal furnace and discharge heated air into the upper part of the coal furnace casing as shown in Fig. 1.

To stimulate the air circulation, I provide a 70 motor driven fan including a motor 55 and fan blades 56, of such capacity that it will easily overcome the added resistance to the air flow brought about by transferring the heated air to the coal furnace instead of passing it directly 75 to the warm air ducts from the furnace top but

not of great enough capacity to pull the heated air downwardly within the casing of the coal furnace. That is, the motor driven fan is of a size and its speed may be varied in proportion to the warm air exhaust capabilities of the furnace. If this latter effect took place, the entire casing of the coal furnace would become warmed and needlessly radiate heat into the furnace room. Of course, such heat radiation might at sometimes be desirable. In other words, 10 the air delivery capacity of the fan is proportioned so that, aided by the natural draft in the auxiliary furnace casing, it will deliver hot air into the dome of the coal furnace substantially as fast as the warm air pipes leading to the various registers can accept it and no faster. In 15 accomplishing the above circulation, a second essential is also accomplished by withdrawing the cold air from the base of the coal furnace fast enough to prevent the entering cold air from 20 being drawn upwardly in the coal furnace casing, mixing with the heated air in the upper parts of the casing, and impairing the air circulation through the warm air ducts to the room. With my construction, the circulating power of 25 the fan may be so adjusted that the air in the vertical middle of the coal furnace casing has practically no tendency to pass either up or down.

It is desirable that the motor fan be placed 30 in the cold air stream between the coal furnace and the auxiliary furnace and, since the auxiliary furnace may of necessity be located very close to the coal furnace with the motor fan blades 56 located outside of the auxiliary furnace casing, the motor fan may be placed partly or entirely within the radius of the coal furnace casing. However, it is desirable that the motor fan be readily accessible and easily removable. 40

As shown in Fig. 3, the motor fan is mounted upon a sliding drawer 57 that may be inserted into its desired location through an opening in the cold air transfer duct 58 provided between the coal furnace and the auxiliary furnace. 45 Strap clamps 59 are provided to hold the motor 55 securely on the drawer, a sheet metal guard 60 protects the motor from heat radiation by intercepting heat rays and dissipating them by convection, and the motor fan is supported on a flexible member 61 attached to the drawer or slide 57 to absorb vibration of the motor fan. A protecting tube 62 may be provided for carrying the current conducting wires 63 to the motor in order to protect them from injury. 55

On the motor fan drawer being disposed in a provided opening in either the front or back of the cold air duct 58, a vertical panel 64 closes the opening and vertical flanges 65 on the panel serve to hold the entire assembly in vertical alignment. A handle 66 is provided on the panel 64 for convenience in withdrawing the motor fan assembly from the cold air duct. 60

Since the cold air duct 58 may be on either the right or left side of the auxiliary furnace depending on which side of the coal furnace the auxiliary furnace is located and as the motor fan must in either case propel air toward the auxiliary furnace, the motor and fan are so mounted that they may be withdrawn from the clamps 59 and be again inserted with the fan blades 56 facing in the opposite direction. This reversible feature is necessary to adapt the motor fan unit to the reversibility or interchangeability of the side panels 3 and 4 as hereinbe- 70 75

fore described to adapt the auxiliary furnace to either side of the existing heating unit. It is also necessary that the fan drawer be of such proportion and construction that the motor fan 5 will be at the proper elevation, be centrally disposed, and have its axis aimed horizontally and at right angles to the auxiliary furnace so that the air stream will be properly distributed within the auxiliary furnace.

10 In order to direct the horizontally incoming air stream, forced into the auxiliary furnace by the motor fan unit just described, upwardly and divide it properly into the upward air passages between and around the heating drums 15 18 and the drum 20, two curved longitudinally disposed air deflectors 67 are placed as shown in Fig. 4. These deflectors are secured at the lower end of the middle drum 18 and are provided as a unit with cross members 68 so that 20 when the furnace is assembled the deflectors may be placed to face the motor fan unit regardless of whether the latter is to the right or the left side of the existing heating unit. These air deflectors not only deflect the air streams upwardly with the least possible loss of kinetic 25 energy, but spread the air out, prevent backwash of air on either side of the motor fan, and divide the air stream so that relative amounts flow into the various vertical passages proportional to 30 the amount of air heating possible to be done in each passage whereby the air will issue from the vertical passages at substantially an equal temperature.

As a further means for properly dividing the 35 incoming air stream, the middle drum 18 is lower than the side drums, see Fig. 5. In fact, the lowermost end of the middle drum 18 is preferably on a level with the vertical middle of the air inlet duct 58 whereby it will intercept and divide 40 the incoming air stream with one-half of the air stream passing upwardly on one side of the drum 18 and the other half passing upwardly on the opposite side of the drum. Further, the side drums 20 have their bottom portions above the 45 air intake opening so that no matter on which side the air intake may be located there will be an ample inlet passage and proper division of the air. This feature enables the maximum heating surface to be properly distributed within 50 the available vertical space in the auxiliary furnace.

To control the circulation of air through the auxiliary furnace and into the coal furnace in such manner that the auxiliary furnace may be 55 segregated from the coal furnace and the coal furnace used alone, a hot air gate 69 is provided in the hot air passage 11 from the auxiliary furnace to the top of the coal furnace. This air gate is pivoted as at 70 with the pivot rod extending outward on each end and a lever 71 keyed to one of the extending ends and projecting upwardly in the plane of the gate 69. A tension spring 72, attached to one end of the lever 71, is anchored to one of the bolts 8 that holds the 65 upper ends of the casing panels together. When the air gate is in its open position, the spring 72 exerts maximum leverage to hold the gate in such position and when the hot air gate is in its closed position as shown in Fig. 15, the spring is 70 substantially in alignment with the gate and the spring anchor whereby it exercises insufficient leverage to lift the hot air gate and the gate remains in its closed position. The lever 71 is also used as a hand lever for moving the air gate from 75 closed to open position and vice versa and the

air gate is necessarily reversible, end for end so that it may be adjacent the coal furnace regardless of whether the hot air outlet 11 is on the right or left side of the auxiliary furnace. To effect this, the side flanges of the hot air opening are such that the pivot extensions of the air gate may be easily removed therefrom.

As a safety means, a thermostatic means is provided for partly opening the air gate 69 should the air gate be in closed position with the burner 19 in operation. This takes the form of a thermometal strip 73 that is secured at its lower end and has its free upper end disposed between the outer face of the air gate 69 and the hot air outlet 11. That is, the strip projects upwardly sufficiently so that the hot air gate will lie against it when closed, see Fig. 15. Should the hot air gate be in closed position and the furnace be lighted, the trapped air within the upper end of the casing will heat the thermometal strip 73 and cause it to bend inwardly toward the center of the auxiliary furnace which will push the air gate 69 outwardly sufficiently for the spring 72 to exert sufficient force on the lever 71 to completely open the gate. The provision of this thermostatic gate opening means prevents overheating and possible damage or fire in the event the air gate 69 should be left closed when the auxiliary furnace is placed in operation by lighting the burner 19. Such thermometal strip may be located at any point longitudinally of the air gate 69 but is preferably located opposite one of the cross tubes 21 where it will receive maximum heat when the furnace is in operation. However, the location of the thermometal strip is such that 35 heat from the coal furnace does not reach the strip sufficiently to cause it to trip the air gate 69.

A gas burner valve 74 of the ordinary tapered plug variety, in which a 90° turn of the valve handle 75 moves the valve rotor from full off to full 40 on position, is provided as a fuel control means. At the inner end of the plug, an arm 76 is secured and a link 77 connects the end of this arm to a second arm 78 which is keyed to a rock shaft 79. This rock shaft extends through to the rearward 45 side of the furnace casing where an arm 80 is keyed to it. This construction will cause the arm 80 to move simultaneously and in proportion with movement of the burner valve rotor.

As shown in Fig. 5, the link 81 extends upwardly from the end of the arm 80 and has its upper end connected to a draft control damper 82 located in the vent duct 23 and pivoted at or near its center as at 84. In my construction, another link 85 connects the draft damper 82 to another 55 damper 86 which provides an air control gate to control the volume of air entrained into the vent pipe leading from the collar 25 to a chimney.

With this construction, the draft damper and air control gate operate simultaneously with the burner valve in such manner that when the burner valve is closed the draft damper 82 and air control gate 86 will be in closed position. Reversely, when the burner valve is open, both the draft damper 82 and air control gate 86 will be open as shown in Fig. 5. Likewise, the draft damper and air control gate will assume positions proportional to the degree of movement of the burner valve.

The burner valve is of preferably such nature that the valve must be turned a substantial distance before the fuel passage therethrough is open whereby the damper and air control gate 82 and 86 will be opened almost half-way before 75

fuel begins to issue from the burner. This feature assures sufficient damper and air control gate opening when the burner is turned on only part way and the parts may be so adjusted that the damper and air control gate are opened proportionate to their needs. This is due to the fact that a larger damper opening relative to volume of fuel burned is necessary when the burning is at a low combustion rate because of the slower travel of the combustion products.

Thus, turning of the rotor of the burner valve 74 automatically controls the combustion products draft openings and hence the volume of combustion products passed into the vent pipe to the chimney is in approximately correct proportion to the amount of gas being burned in the auxiliary furnace. This reduces excess of air in the combustion products passing to the vent pipe and hence prevents a large drop in efficiency when the burner valve is turned on only part way. Likewise, the air gate, by reducing the amount of opening to suit the immediate needs, reduces the entrained air at the draft hood 24 when the burner valve is turned on only part way which tends to reduce condensation in the vent pipe by reducing chilling of the combustion products flowing from the auxiliary furnace to below the dew point due to excess air intermixture. When the burner valve is completely turned off, both dampers are simultaneously closed with no attention necessary by the operator which prevents escape of hot combustion products retained in the drums 18 and 20 so that their contained heat may be passed into the air which circulates through the auxiliary furnace.

Automatic closure of the air gate 86, when the furnace is not in operation, stops inflow of air through the draft hood 24 and into the vent pipe to the chimney which prevents chilling of the vent system during off periods if the system is under thermostatic control, and, when the auxiliary furnace is vented into the smoke pipe of the coal furnace as is preferred, prevents checking of the coal furnace draft when the auxiliary furnace is not being used. Thus, the draft for the coal furnace is not impaired when the coal furnace is used alone. The fact that the draft damper 82 closes simultaneously with the burner valve to prevent escape of the combustion products, makes similar automatic closure of the air gate 86 and direct venting of the auxiliary furnace into the coal furnace smoke pipe practicable. However, a slight leakage may take place around the draft damper 82 to have it practical for a standby pilot burner to be provided in the auxiliary furnace, and the parts are so constructed and located that, should the operating mechanism break, the dampers will gravitate to open position. This is an added safety feature.

The air gate 86, shown in its extreme open position in Fig. 5, also acts as a down draft baffle to prevent downward drafts through the smoke pipe from reaching the outlet of the vertical vent duct 23. This air gate with the open bottomed hood 24 forms a rectangular-shaped draft hood having well known functions but with the added feature of having a closable outlet. This is accomplished by combining air gate and baffle in one member.

As hereinbefore stated, a single gas valve is provided and, for convenient lighting, the hereinbefore described burner is located immediately inside a fire door 87 with the burner top level with the bottom of the fire door. Ordinarily, an oper-

ator turns on full gas supply when lighting the burner which causes flaring out of the flame through the fire door. Therefore, means are provided which makes it impossible to turn on full gas supply while the fire door 87 is open. This means consists of a bell crank 88 pivoted at some point on the burner valve rotor with a link 89 connecting one end of the bell crank to the fire door, the connection being located at the proper distance from the hinge axis of the door to provide a lever which, when the fire door 87 is opened, moves the bell crank 88 about its axis by means of the connecting link 89. The bell crank is so arranged that one arm 90 thereof will then be moved so that it interferes with and prevents full movement of the arm 78 connected to the burner valve rotor and which is actuated by turning the burner valve rotor through the arm 77 attached thereto as has previously been described.

In my preferred construction, the arm 78 is provided with a projecting lug 91 in which an adjusting screw is so located that it will strike the end of the bell crank arm 90 when the fire door 87 is open as shown in Fig. 9. This screw may be so adjusted that the fire door may be opened and the burner valve handle turned toward "on" position until its movement is stopped by interference by the lug 91 with the arm 90. Further, this adjustment may be such that the burner valve may be turned just sufficiently for proper ignition without having the flame from the burner flare out at the fire door. After ignition, the fire door is closed whereupon the bell crank arm 90 will be moved out of interference as shown in Fig. 8 and the burner valve can be turned on in full. Such construction compels a safe and proper ignition of the burner and the construction may be varied so long as a means is provided for interfering with full burner valve opening until the fire door 87 is closed.

In the operation of this auxiliary furnace, secondary air for combustion enters the space below the burner through the air inlet opening below the mixer, this air being drawn from without the gas furnace structure. The air enters the space 53 below the burner 19 and travels upwardly through the restricted slots 49, 50 and 51 to feed the flame jets issuing from the burner. Of course, it will be understood that fuel issuing from the burner has previously been ignited and the draft dampers are in open position. Combustion takes place in the space 54 above the burner, and the products of combustion pass upwardly in the middle drum 18, divide at the top into the tubular connecting ducts 21 through which the products pass into the side drums 20.

In the side drums, the products of combustion contract and become heavier as they give up their heat, gradually gravitating to the bottom, with the amount and speed of downward flow in the two or more side drums tending to balance. That is, if one side drum loses more heat than the other, more products of combustion gravitate through it and the temperature of the burned gases at any given level are substantially alike in both side drums and are of progressively lower temperatures at lower levels.

When the combustion products are sufficiently cool to reach the bottom of the side drums 20, they pass from the bottom rear ends of the side drums into the hollow vent manifold casting 22, thence upwardly through the vertical vent passage 23 which vents into the open draft hood 24, and thence through an outlet opening 25 into a

vent pipe that leads to the chimney of the coal furnace.

The downward circulation of products of combustion in the side drums is due mostly to gravity because, the middle and side drums are in communication at the top, and the gases in the side drums are cooler and of heavier specific gravity than the hotter and hence lighter gases in the middle drum, whereby the gases in the side drums naturally gravitate toward the bottom thereof. That is, the products are not entirely forced downwardly in the side drums by the forced upward movement thereof in the middle drum 18 nor are they entirely moved by being siphoned out at the bottom of the side drums by the upward draft in the vertical vent duct 23. It is true that both of these effects help the flow of the products but without a natural gravitational drop this help would not be sufficient to maintain a free draft starting with a cold furnace, and would not be sufficient to cause movement of the burned gases away from the burner throughout its length fast enough to prevent choking of the flames and impartial combustion. In larger sizes of furnaces, employing more than one down draft drum on each side of the middle drum, and therefore having a greater proportion of heat transfer surface extracting heat during the downward travel of the combustion products, this gravitational assistance to the normal tendency of combustion products to flow upwardly is very pronounced.

Further, the free circulation of combustion products through the furnace make it possible to employ a rear vent passage 23 of very small rise, hence the draft hood 24 and vent outlet 25 may be low in elevation. This is important in auxiliary furnace structures because it is desirable to vent the auxiliary furnace directly into the smoke pipe of the main heating unit which is usually at relatively low elevation. This eliminates the need of a separate vent pipe to the chimney. The freedom of draft secured within the furnace makes possible, not only a low rear vent connection capable of being connected to the smoke pipe with an upward pitch between the draft hood and the smoke pipe, but it also makes possible the restricted secondary air openings at the burner and gives a rapid pick-up of the draft when the burner is started at full capacity.

The circulation of the air to be heated through the auxiliary furnace is in an upward direction between and around the drums 18 and 20 as shown by the arrows in Fig. 4, the air being drawn inwardly by the fan structure hereinbefore described and forced outwardly at the top of the furnace through the outlet 11 past the air gate 69 and into the top of the main heating unit or furnace structure. It should be noted that just before the combustion products leave the side drums they are exposed to the greatest heat extracting or cooling influence possible, that is, that of the incoming cold air.

The air around the side drums flows in a direction opposite to that of the combustion products within the side drums which results in progressively greater heating influence upon the air as it travels upwardly and progressively greater cooling influence upon the combustion products as they travel downwardly. Just before the air reaches the furnace structure opening 11, it is exposed to the influence of the hottest heating surface with the result that the greatest average temperature difference exists between the heating surface and the air which is possible to achieve upon a practical basis. This, in turn, results in

the greatest possible heat transfer per square unit of the heating surface. Such direct and practically unimpeded upward flow of the air to be heated provides a strong air circulation which is a very desirable feature in an auxiliary furnace.

With the construction above described it is possible to use either the main heating unit or the auxiliary furnace alone or use them simultaneously and in combination. In using the main heating unit alone the gate controlling the flow of hot air to the main heating unit is closed as well as the combustion draft dampers of the auxiliary furnace. In using the auxiliary furnace alone, no change is made in the main heating unit inasmuch as the flow of heated air is upwardly and directed into the main heating unit at substantially the point at which heated air is removed from the main heating unit to be delivered to the room register or other equipment.

What I claim is:

1. In combination with a main furnace of the warm air type, an auxiliary warm air furnace comprising a casing including a front panel, a back panel, interchangeable side panels, said front, back and side panels being adapted to fit together at their adjoining edges, an air heating means within said casing, and a warm air outlet in one of said interchangeable side panels adapted for duct communication with the interior of said main furnace.

2. In combination with a main furnace of the warm air type, an auxiliary warm air furnace comprising a casing including a front panel, a back panel, interchangeable side panels, said front, back and side panels being adapted to fit together at their adjoining edges, an air heating means within said casing, a warm air outlet in one of said interchangeable side panels adapted for duct communication with the interior of said main furnace, and a closure for said warm air outlet.

3. In combination with a main furnace of the warm air type, an auxiliary warm air furnace comprising a casing including a front panel, a back panel, interchangeable side panels, said front, back and side panels being adapted to fit together at their adjoining edges, an air heating means within said casing, a warm air outlet in one of said interchangeable side panels adapted for duct communication with the interior of said main furnace, a closure for said warm air outlet, and thermostatic means for causing opening of said closure under the influence of heat.

4. In combination with a main furnace of the warm air type, an auxiliary warm air furnace comprising a casing including a front panel, a back panel, interchangeable side panels, said front, back and side panels being adapted to fit together at their adjoining edges, air heating means within said casing, a warm air outlet in one of said interchangeable side panels adapted for duct communication with the interior of said main furnace, and a cold air inlet in one of said interchangeable side panels.

5. In combination with a main furnace of the warm air type, an auxiliary warm air furnace comprising a casing including a front panel, a back panel, interchangeable side panels, said front, back and side panels being adapted to fit together at their adjoining edges, air heating means within said casing, a warm air outlet in one of said interchangeable side panels adapted for duct communication with the interior of said main furnace, and a cold air inlet in one of said

interchangeable side panels and adapted for duct communication with the interior of said main furnace.

6. In combination with a main furnace of the warm air type, an auxiliary warm air furnace comprising a casing including a front panel, a back panel, interchangeable side panels, said front, back and side panels being adapted to fit together at their adjoining edges, air heating means within said casing, a warm air outlet in one of said interchangeable side panels adapted for duct communication with the interior of said main furnace, and a cold air inlet in one of said interchangeable side panels and adapted for duct communication with the lower interior of said main furnace.

7. In combination with a main furnace of the warm air type, an auxiliary furnace comprising a casing including a front panel, a back panel, interchangeable side panels, a reversible top panel, said front, back and side panels being adapted to fit together at their adjoining edges, an air heating means within said casing, and a warm air outlet in one of said interchangeable side panels adapted for duct communication with the interior of said main furnace.

8. In combination with a main furnace of the warm air type, an auxiliary furnace comprising a casing including a front panel, a back panel, interchangeable side panels, a reversible top panel, said front, back and side panels being adapted to fit together at their adjoining edges, an air heating means within said casing, a warm air outlet in one of said interchangeable side panels and adapted for duct communication with the interior of said main furnace, and a cold air inlet in said casing.

9. In combination with a main furnace of the warm air type, an auxiliary furnace comprising a casing including a front panel, a back panel, interchangeable side panels, a top panel, said front, back and side panels being adapted to fit together at their adjoining edges, an air heating means within said casing and supported exclusively by said front and back panels, and a warm air outlet in one of said interchangeable side panels and adapted for duct communication with the interior of said main furnace.

10. In combination with a main furnace of the warm air type, an auxiliary furnace comprising a casing including a front panel, a back panel, interchangeable side panels, a top panel, said front, back and side panels being adapted to fit together at their adjoining edges, an air heating means within said casing and supported exclusively by said front and back panels, a warm air outlet in one of said interchangeable side panels and adapted for duct communication with the interior of said main furnace, and a cold air inlet in said casing.

11. In combination with a main furnace of the warm air type, an auxiliary warm air furnace comprising a casing including a front panel, a back panel, interchangeable side panels, said front, back and side panels being adapted to fit together at their adjoining edges, an air heating means within said casing, a warm air outlet in one of said interchangeable side panels

and adapted for duct communication with the interior of said main furnace, and a reversible closure for said warm air outlet.

12. In combination with a main furnace of the warm air type, an auxiliary furnace comprising a casing including a front panel, a back panel, interchangeable side panels, a reversible top panel, said front, back and side panels being adapted to fit together at their adjoining edges, an air heating means within said casing, and a warm air outlet in one of said interchangeable side panels and adapted for duct communication with the interior of said main furnace, said reversible top panel being inclined upwardly toward said warm air outlet.

13. In combination with a main warm air furnace, an auxiliary warm air furnace comprising a casing including a front panel, a back panel, interchangeable side panels, said front, back and side panels being adapted to fit together at their adjoining edges, an air heating means within said casing, and a cold air inlet and a warm air outlet in one of said interchangeable side panels, said warm air outlet having duct communication with the interior of said main furnace.

14. In combination with a main warm air furnace, an auxiliary warm air furnace comprising a casing including a front panel, a back panel, interchangeable side panels, said front, back and side panels being adapted to fit together at their adjoining edges, an air heating means within said casing, and an air inlet and a warm air outlet in one of said interchangeable side panels, both said inlet and said outlet having duct communication with said main furnace.

15. In combination with a warm air heating furnace, an auxiliary warm air furnace comprising a casing including a front panel, a back panel, interchangeable side panels, said front, back and side panels being adapted to fit together at their adjoining edges, an air heating means within said casing, an air inlet and a warm air outlet in one of said interchangeable side panels, both said inlet and said outlet having duct communication with said main furnace, and an air moving means in said air inlet duct.

16. An auxiliary warm air furnace, comprising a casing including front and back panels, interchangeable side panels of equal height, a reversible top panel, a heating means within said casing, and a warm air outlet in one of said interchangeable side panels and adapted for duct communication with a main warm air furnace, said top panel being inclined upwardly toward said warm air outlet.

17. In combination with a main warm air furnace, an auxiliary warm air furnace comprising a casing, an air heating means within said casing, an air inlet to said casing, a warm air outlet therein, ducts connecting said air inlet and said warm air outlet with the interior of said main furnace, and an air flow accelerating means for said auxiliary furnace including a fan structure in said air inlet duct, said fan structure being reversibly mounted on a supporting frame and being withdrawable as a unit from said duct.

OTTO J. KUENHOLD.
